UNITED STATES PATENT OFFICE.

HARVEY BIRCHARD TAYLOR, OF PHILADELPHIA, PENNSYLVANIA.

TURBINE-GATE-OPERATING MECHANISM.

Application filed July 29, 1922. Serial No. 578,393.

To all whom it may concern:

Be it known that I, HARVEY BIRCHARD TAYLOR, a citizen of the United States, residing at Philadelphia, in the county of Philadelphia and State of Pennsylvania, have invented certain new and useful Improvements in Turbine-Gate-Operating Mechanism, of which the following is a specification.

This invention relates to turbine gate operating mechanism and particularly to operating mechanism for turbine gates of the wicket type controlled by linkages from a common operating ring. In prior practice it has been usual to move the operating rings by fluid pressure in a pair of operating cylinders having parallel pistons on opposite sides of the ring. This has involved a considerable extension of the overall dimensions necessary for the operating mechanism and has required the running of long piping connections to the opposite cylinders.

The object of the present invention is to provide operating mechanism of reduced overall dimensions such that both cylinders may be compactly assembled within a single chamber alongside of the operating ring and with short fluid pressure pipe connections between the cylinders.

In the accompanying drawings illustrating the invention

Fig. 1 is a plan view of a portion of a turbine gate operating mechanism,

Fig. 1^a is a diagram illustrating the action of the operating forces in the Fig. 1 mechanism,

Fig. 2 is a view similar to Fig. 1 showing a different form of turbine.

Fig. 3 is a vertical sectional view on line 3—3 of Fig. 2, and

Fig. 4 is a vertical sectional view on line 4—4 of Fig. 2.

In the plan view shown in Fig. 1 the invention is illustrated as applied to the ordinary conventional setting of turbine with a downward discharge and with the operating ring inside the guide vane circle. In this structure a pit liner 5 with flange 6 surrounds the floor plate 7 of the turbine cover plate above which is mounted the operating mechanism. The stems of the guide vanes extend upward through the cover plate and have keyed thereon the arms 8 connected by links 9 of the operating ring 10 turning on bearings 11 supported from the turbine cover plate.

To move the operating ring 10 and adjustable guide vanes the cylinders A and B are provided having their axes on the same side of the operating ring and meeting at an angle α which in the specific embodiment shown is less than 90° . This permits the cylinders A, B to be positioned in a single chamber close together and thus saves in the over all dimensions of the operating mechanism. This chamber is provided by an extension 12 of the pit liner 5, the head ends of the cylinders A, B being fastened to the walls of the extension at 13, 14.

In order to rotate the operating ring 10 to move the vanes, fluid pressure is admitted to cylinders A, B. For clockwise movement of the operating ring pressure is admitted through the pipe opening 15 to the rod end of cylinder A and the head end of cylinder B while pressure is exhausted from the opposite ends of these cylinders through pipe opening 16, the pipe openings 15 and 16 being connected to any desired remote point of supply and control. To reverse the movement of ring 10 pressure will be supplied through pipe opening 16 and exhausted through pipe opening 15. The crossover piping 15', 16' is arranged as a single casting bolted to the two cylinders and it may also be desirable, for instance in small installations, to form the cylinders A, B as a single casting.

With the cylinders A, B thus located together, housing means for the cylinders need be provided only on one side of the pit liner in the most convenient location with relation to the remainder of the installation. The cross connections of piping between the cylinders is also simplified and shortened and in case of inspection or repair both cylinders are accessible at the same time in a single compartment.

With the operating mechanism of this invention there is a small resultant side thrust produced by the action of the rods a , b against the bearings 11 supporting the operating ring. This is shown diagrammatically in Fig. 1^a. The side thrust produced by two parallel cylinders is equal to the numerical difference of the forces F_A and F_B . If a single cylinder is used, it must produce a force equal to $F_A + F_B$, and the side thrust on the operating ring bearing is also equal to $F_A + F_B$. The arrangement comprising this invention requires a somewhat greater side thrust F_c on the bearing than two par-

allel cylinders, but this side thrust is very much smaller than that which would be produced by a single cylinder. It will be noted from the diagram of Fig. 1^a that for the particular angle α employed in Fig. 1 the value of F_c is considerably less than either F_A or F_B and is therefore quite small in comparison with the sum of F_A and F_B . In general F_A and F_B will not be exactly equal owing to the area of the piston rod or piston trunk. In cases where F_A is approximately equal to F_B , as shown in dotted lines in Fig. 1^a, the side thrust on the bearing would amount to approximately

$$15 \quad F_c = 2F_A \sin \frac{\alpha}{2}$$

It is therefore seen that a very convenient and compact arrangement of the operating 20 cylinders and pistons can be secured by this invention without causing any excessive side thrust against the operating ring bearing..

In the modification shown in Figs. 2, 3 and 4 the invention is illustrated in connection with an inverted turbine with the operating ring outside of the vane circle. In this turbine the flow enters horizontally through the speed ring 20 and guide vanes 21 and then turns upwardly to pass through 25 the runner (Fig. 3). The pit liner 25 by its lower flange 26 supports the turbine casing ring 27 through which pass the stems 28 of the movable guide vanes 21. An operating ring 30 rotates in bearings 31 formed on the 30 inner surface of the pit liner 25 and this operating ring carries studs 32 linked as indicated at 33 to the arms 34 of guide vane stems 28. The pit liner 25 is supported from the speed vane ring 20 as shown.

40 To move the operating ring 30 and adjustable guide vanes 21 cylinders A', B' are provided positioned in the chamber 42 formed by extensions of the pit liner 25 and connected by rods a', b' to the operating 45 ring. The rods a', b' have their axes at an angle α' greater than the angle α (Fig. 1) but less than 90°. Crossover pipes 35, 36 are provided for connecting the opposite ends of the cylinders A', B' to pressure and 50 exhaust as in Fig. 1 and the operation of this mechanism is in general similar to the described operation of the Fig. 1 mechanism.

In both the structures of Fig. 1 and Fig. 2 the chamber containing the operation cylinders A, B, or A', B' are shown located 55 adjacent the small portion of the volute casing as indicated in dotted lines at v, v', where there is ample room for these cylinders. The mechanism of this invention is thus easily adaptable to the special conditions 60 of individual installations and while the invention has been illustrated in connec-

tion with specific structures it is not confined thereto but is intended to cover such modifications thereof as fall within the scope 65 of the appended claims.

I claim:—

1. A hydraulic turbine having a series of gates and a pair of operating cylinders for actuating said gates, said cylinders having 70 non-parallel axes.

2. A hydraulic turbine having a series of gates and a pair of operating cylinders for actuating said gates, said cylinders having 75 non-parallel axes and being located closely adjacent to each other.

3. A hydraulic turbine having a turbine pit and operating mechanism contained within said pit, and a pair of operating cylinders for actuating said mechanism, said cylinders having non-parallel axes and being contained within a single recess in the wall of said pit. 80

4. In a hydraulic turbine a gate operating mechanism comprising a pair of cylinders containing fluid pressure operated pistons connected to an operating ring, said cylinders having non-parallel axes. 85

5. In a hydraulic turbine a gate operating mechanism comprising a pair of cylinders containing fluid pressure operated pistons connected to an operating ring, said cylinders having non-parallel axes and being located closely adjacent to each other. 90

6. In a hydraulic turbine a gate operating mechanism comprising a pair of cylinders containing fluid operated pistons connected to an operating ring by means of pin connections, the axes of said cylinders being non-parallel and substantially tangent to a 100 circle about the turbine axis containing said pin connections.

7. In a turbine gate operating mechanism the combination with an operating ring of a pair of operating cylinders therefor having axes on the same side of said ring and meeting at an angle of less than 90°. 105

8. In a turbine gate operating mechanism the combination with a turbine pit of an operating ring rotatably mounted within 110 said pit, a chamber forming a recess in the wall of said pit and a plurality of non-parallel operating cylinders positioned in said chamber and connected to move said operating ring. 115

9. A hydraulic turbine having a turbine pit liner and operating mechanism contained within said liner, and a pair of operating cylinders for actuating said mechanism, said cylinders being contained within 120 a single chamber formed by an extension of the walls of said liner.

HARVEY BIRCHARD TAYLOR.
